US00D604501S

(12) **United States Design Patent**
Lee

(10) **Patent No.:** US D604,501 S
(45) **Date of Patent:** ** Nov. 24, 2009

(54) **EARPHONE CARRYING CASE**

(76) Inventor: **In Cheol Lee**, 2 Spruce Pl., Great Neck, NY (US) 11021

(**) Term: **14 Years**

(21) Appl. No.: **29/324,146**

(22) Filed: **Sep. 8, 2008**

(51) **LOC (9) Cl.** 03-01

(52) **U.S. Cl.** D3/201

(58) **Field of Classification Search** D3/294-295, D3/201, 203.1, 203.3, 203.6, 205, 272-273, D3/301, 218; D9/418, 420, 426, 428, 432; 206/37, 229, 320, 363, 557; 220/810, 825, 220/833-835; D28/82

See application file for complete search history.

(57) **CLAIM**

The ornamental design for the earphone carrying case, as shown and described.

DESCRIPTION

FIG. 1 shows a left side view of the carrying case in a fully open position.

FIG. 2 shows a top perspective view of the carrying case in a fully open position.

FIG. 3 shows a top plan view of the carrying case in a fully open position.

FIG. 4 shows a top perspective view of the carrying case in a closed position.

FIG. 5 shows a front side view of the carrying case in a closed position.

FIG. 6 shows a side view of the carrying case in a closed position.

FIG. 7 shows a top plan view of the carrying case in a closed position.

FIG. 8 shows a rear side view of the carrying case in a closed position.

FIG. 9 shows a top, rear perspective view of the carrying case in a closed position.

FIG. 10 shows a top perspective view of the carrying case in a partially open position.

FIG. 11 shows a top plan view of the carrying case in a partially open position.

FIG. 12 shows a side view of the carrying case in a partially open position.

FIG. 13 shows a front side view of the carrying case in a partially open position.

FIG. 14 shows a top perspective view of the carrying case open 45 degrees.

FIG. 15 shows a top perspective view of the carrying case open 45 degrees.

FIG. 16 shows a side view of the carrying case open 45 degrees; and,

FIG. 17 shows a front side view of the carrying case open 45 degrees.
